Charles A. Lind

ATTORNEY.

UNITED STATES PATENT OFFICE

ERNEST G. DE CORIOLIS, OF TOLEDO, OHIO, ASSIGNOR TO SURFACE COMBUSTION CORPORATION, OF TOLEDO, OHIO, A CORPORATION OF NEW YORK

FURNACE

Application filed September 8, 1930. Serial No. 480,353.

This invention relates to improvements in furnaces wherein work may be heated without contact with the furnace gases and has for its general object to provide in combination with a heating furnace, a work holding container which may be entered into and removed from the furnace through a door opening in one end thereof, the container being provided with means for agitating the atmosphere within the container and means being provided for introducing into the container from outside of the furnace a fluid for maintaining the desired atmosphere within the container.

15 The invention has been evolved more particularly for use in connection with the nitriding of various metallic articles, such articles requiring an atmosphere of ammonia gas during the heat treating operation 20 but the invention is not limited in its application to such use.

For a more complete understanding of the invention, reference is made to the detailed description taken in connection with 25 the accompanying drawing wherein the preferred form of the invention is shown.

The single figure of the drawing is a vertical longitudinal section through a box type furnace and showing the container 30 and mechanism associated therewith.

The furnace itself is a refractory structure of box-like form, having a roof or arch 1, a floor 2, end walls 3 and 4 respectively, and side walls 5; the end wall 3 having a 35 door opening 6 normally closed by a door 7 and the opposite end wall 4 having an aperture 8 for a purpose hereafter mentioned. Extending longitudinally of the furnace and through the door opening 6 thereof, is a track bed 9 suitably supported 40 at opposite ends of the furnace and positioned intermediate the floor and roof thereof to permit underfiring by burners 10 and overfiring by burners 11 positioned on the 45 side walls of the furnace. 12 indicates an opening in the furnace roof through which products of combustion may escape from the furnace.

15 indicates generally a box-like container preferably made of metal and having re-

movable cover 16 adapted to make a gas tight fit with the container in any suitable manner as by a sand seal indicated at 17. In this container the articles to be heat treated will be placed before the container 55 is introduced into the furnace, it being understood that the container is removable from the furnace through the door opening 6, and is moved into the furnace through said opening by being moved along the supporting bed 9.

Projecting from one end of the container 15 is a longitudinally extending bracket generally indicated at 18, this bracket being shown as of such form that it forms a closure for one end of the container. The bracket is also of such form that it may extend through the aperture 8 in the furnace wall 4 and has a longitudinally extending bore wherein is positioned a hollow rotatable 70 shaft 19 supported in suitable bearings 20 positioned in the bore of the bracket. This shaft is of sufficient length to project beyond the ends of the bracket 18 and mounted on the shaft within the container 15 is a fan 21, this fan being adapted to be rotated by the shaft. 22 indicates a packing nut at the outer end of the bracket for maintaining a tight joint between the shaft and the bracket 75 as will be readily understood. The outer end of the shaft 19 is adapted to be removably connected to a rotatable hollow shaft 23 mounted for rotation in a bracket 24 secured to the outer face of the furnace wall 4. 25 indicates a driving pulley secured to the shaft 23 for rotating it and hence also the shaft 19. 26 indicates a pipe suitably coupled to the shaft section 23, for introducing into the container a fluid such as ammonia gas, this pipe being connected to a suitable source of supply not shown.

27 indicates set screws which may be used for preventing longitudinal movement of the container while in the furnace, it being understood that these screws are backed away from the bracket 18 when it is desired to remove the container from the furnace. It will, of course, also be understood that the shaft section 23 is uncoupled from the 80 85 90 95

shaft 19 when the container is to be removed from the furnace.

28 indicates a screen within the container 15 forming a partition therein in front of the fan 21 to provide a compartment 29 for the latter. This screen not only protects the fan from damage by articles in the container but also causes the gas entering the container 15 through the shaft 19 to spread 10 out more effectively in front of the fan before being forced into the main compartment of the container.

The wall of the container opposite the fan is provided with one or more relatively 15 restricted apertures 30 through which spent gas may pass from the container in order to permit continuous introduction into container of fresh gases. There is preferably provided in connection with the aperture 30 20 on the outside of the container a flap cover 31 which will open under pressure within the container to permit gases to flow through the vent or aperture 30 but which will seal the vent against the entrance of 25 furnace gases into the container.

From the foregoing description it will be seen that the present invention contemplates that the container shall be loaded with materials to be heat treated while the container 30 is outside of the furnace. The cover 16 is then placed on the container and the container moved into the furnace. The bracket 18 will extend through the aperture 8 in the furnace wall 4 and the shaft 19 will be 35 coupled to the shaft extension 23 in order that the fan may be rotated. After the heat treating operation is complete the container is withdrawn from the furnace, the driving connection between the shafts 19 40 and 20 being first uncoupled as will be readily understood.

What is claimed is:

1. In combination, a furnace, a work-holding container removably positioned in the furnace, a fan within said container at one end thereof, a hollow drive-shaft on which said fan is mounted, said shaft extending outside of the container and furnace, and means coupled to the outer end of the shaft 45 for introducing fluid into said container.

2. In combination, a furnace, a work-holding container removably positioned in the furnace, a shaft-supporting bracket secured to said container and projecting 55 through a wall of the furnace, a hollow drive-shaft supported by said bracket, a fan within the container and secured to said shaft, said shaft extending outside of the container and furnace, and means coupled 60 to the outer end of the shaft for introducing fluid into said container.

3. In combination, a furnace, a work-holding container removably positioned in the furnace, a fan within the container at 65 one end thereof, a screen in front of said

fan, and a hollow drive-shaft on which said fan is mounted, said shaft extending outside of said container and furnace, and means coupled to the outer end of the shaft for introducing fluid into said container.

4. In combination, a box-type furnace having a door opening in one end wall thereof and an aperture in the opposite end wall, a container positioned in the furnace and removable therefrom through said opening, a bracket projecting from said container and adapted to enter said aperture, a fan within said container, and a hollow drive-shaft supported by said bracket for rotating the fan, and means coupled to the outer end of the shaft for introducing fluid into the container.

5. The combination with a furnace having a door opening in one end thereof and an aperture in its opposite end wall, of a box adapted to be inserted into and removed from furnace through said door opening, a body forming an extension of one end of the box and adapted to project into said aperture, a hollow driving shaft extending through said body from within the box, a fan within the box and driven by said shaft, means outside of the furnace for driving said shaft and means outside of the furnace for passing fluid through said shaft into 95 said box.

In testimony whereof I affix my signature.
ERNEST G. DE CORIOLIS.
